M. Mettee,

Pump Lever.

Patented May 20, 1830.

William Miller of Baltimore State of Maryland.

Letters Patent.

The Schedule referred to in these Letters Patent and making part of the same, containing a description in the words of the said William Miller of his improvement in Pumps:

To all to whom these presents shall come,
Be it known that I William Miller of the City and County of Baltimore and State of Maryland, have invented a new and useful improvement in Water Pumps (or land pumps) the object of which is to prevent the introduction of foreign substances through the top spout and handle mortise of the same, so as to impede the operation of the piston and of which the following is a full and exact description of the construction and operation of the same as improved by me.

1st. The piston (most commonly called by pump makers the neck of the handle) is welded or united to the pin (or quid, quon) of the same forming one solid piece terminating at said pin, then about an inch from the right side of said neck, the pin is shouldered in square, then a square hole is punched in the upper end of the lever, or that part of the handle which hangs outside of the pump which is then heated and drove on to the square shoulder of said pin as it costs it becomes very tight and close by shrinking it in as commonly the 2 ends of the pin (viz) from the lever or handle on the right side and from the piston or neck on the left) is rounded about an inch each, where they play on the piston top during the operation of the handle, two steel foors are then made and put on the 2 ends of the pin, loosely to wire in some manner as piston collar to prevent the casting from cut out as soon.

2nd. To look at the upper end of the piston instead of round it be square or at right angles, and after it is broken on the

Opposite page

up, a spring key is dropped into it, so that the piston can be unhooked, without taking out the handle, it is also calculated to last longer the piston being more regular than in a round bent handle, which cuts out tolerable soon, in

35^d The fulcrum key is made of cast iron (or wood if most convenient), the lower part of which from the fulcrum pin downwards is permanently fastened to the pump by 5 square headed bolts secured into the wood, the other half, say from the pin, upwards, is fastened to the lower part by a joint hinge, the joint of which is thrown about one inch or more down from the centre (or that part when the two castings separate from each other), the object of which is to throw the upper casting some what off when opened in order to slip out the handle from the right side, or from where the pin is fastened on the casting.

There is also a flange or cap at the right & left of the centre of the casting which completely hides the two ends of the pin as also another on the upper and lower part of said casting, which fits tolerably close around the pin, in the space between the necks and bases, (or handle) the handle playing between said flange on its left, and the bearing for the pin in the casting on its right, the upper casting has also a projection or swell about $2\frac{1}{2}$ inches wide in the centre thereof, commencing at the pin, and gradually diminishing to nothing before it goes under the upper end, this is to prevent the fulcrum or neck from striking against the same during the operation of the handle, the handle as may be expected hangs about two inches or more out of centre to the right side of the pump, nothing is done of the neck and pin which is completely swathed in the said ~~fulcrum~~ key or casting which also entirely encloses the motion of the handle.

46^d The bell cap at the top of the pump, has a slot running across and divided to the upper part of the same to

X 595

present its splitting with the sun, said plate has a pair of fastened down and to the pump, and at the other it is fastened down to a 1/4 inch with a hole in the end and a square headed bolt screwed through the same, also into the pump, there is also a small plate secured on to the under part of the aforesaid turned cap. with one end bent (bend about an inch, which looks over the upper casting when the cap is close down), which leaves the same (casting) close up to the pump, and when any expenses are wanting, there is nothing to do but take out the aforesaid turned screw bolt which fastens down the aforesaid half plate (which secures the cap) and all comes apart immediately.

54. As the pumps are now made to taper upwards, a band is down down set on which rests the full moon box said band prevents the pump from splitting with the sun.

16. The spout is made of cast iron with a plate or flange secured or bolted to the pump it then has a knee about 3 or 4 inches down along side the pump, it then passes out in a straight line as usual parallel with the part which runs into the pump, the nozzle of said spout is turned down about an inch and a half similar to a still cock, and has a grating cast in the same about an inch and a half up from the lower extremity of the same, a hook is cast on the top of said nozzle for the bucket to hang upon the part which runs into the pump is an inch longer in diameter than the outside part, in order to admit of 2 half headings or semicircular pieces placed on opposite sides, the one it makes in from the other, so that the water goes into the pipe along one side and then turns along the other side, and then out.

The old square headed bolt is screwed into the pump just above the pump and within about an inch below the head of the pump and 3 more & little above, secured into

3 of the other angles, the object of which is to prevent the water
from running or splashing with the sun, as they
generally do, I forgot to mention that a circular opening is
also put in the front at the extremity of the inner end,
which runs into the pump, perhaps I shall never have any
occasion to make use of the last mentioned opening, though
of the aforementioned headings yet I will be have them in
the Pattern.
